EXPANSIBLE LINK CHAIN FOR A BRACELET OR SIMILAR ARTICLE

Murray L. Cowan, Norwood, Mass., assignor to
Textron Inc.

Filed Sept. 27, 1974, Ser. No. 509,792

Term of patent 14 years

Int. Cl. D11—01

U.S. Cl. D45—4 E

FIG.1

FIG.2

FIG.3

FIG.4

FIG.5

FIG.6

FIG. 1 is a top plan view of an expandable link chain for a bracelet showing my new design with the links in contracted position;

FIG. 2 is a view similar to FIG. 1 with the links in an expanded position, portion of the conventional appearing bottom links being visible between the expanded top links;

FIG. 3 is an enlarged top plan view of one of the longer top links of the expandable chain;

FIG. 4 is an enlarged perspective view of the top link shown in FIG. 3;

FIG. 5 is an enlarged top plan view of one of the shorter top links of the expandable chain; and

FIG. 6 is an enlarged perspective view of the top link shown in FIG. 5.

The characteristic features of the design reside in the ratio of the body length of the I-shaped top links to the width of the wings thereof and in the spaces between the ends of the bottom links, and the wings of the I-shaped links in their expanded positions.

I claim:

The ornamental design for an expandable link chain for a bracelet or similar article, substantially as shown and described.
